CLOTHES HANGER BAR FOR ATTACHMENT TO A SHELF EDGE

Joe B. Ramsey, Walnut, Calif., assignor to Acme General Corporation, Monrovia, Calif.

Filed Dec. 21, 1970, Ser. No. 26,585

Term of patent 14 years

Int. Cl. D6—99

U.S. Cl. D6—85

FIG. 1

FIG. 2

FIG. 1 is a perspective view of a clothes hanger bar for attachment to a shelf edge showing my design; and

FIG. 2 is a cross section through the clothes hanger bar for attachment to a shelf edge of FIG. 1.

The break lines in the central portion of FIG. 1 indicate indeterminate length for the clothes hanger bar.

I claim:

The ornamental design for a clothes hanger bar for attachment to a shelf edge, as shown and described.
